CLAIM

The ornamental design for a pen needle inner shield, as shown and described.

DESCRIPTION

FIG. 1 is a bottom perspective view of a pen needle inner shield embodying our new design;

FIG. 2 is a top perspective view of the pen needle inner shield shown in FIG. 1;

FIG. 3 is a bottom view of the pen needle inner shield shown in FIGS. 1 and 2;

FIG. 4 is a side view of the pen needle inner shield shown in FIGS. 1-3;

FIG. 5 is a top view of pen needle inner shield shown in FIGS. 1-4; and,

FIG. 6 is a side cross-sectional view, taken along the line 6-6 in FIG. 3, of the pen needle inner shield shown in FIGS. 1-5. The dashed broken lines in the drawings represent portions of the pen needle inner shield that form no part of the claimed design.
